SURFACING PLATE

Vernon G. Hecht, Cincinnati, Ohio, assignor to
 The Meyer-Hecht Company, Cincinnati, Ohio,
 a corporation of Ohio

Application February 26, 1934, Serial No. 712,981

9 Claims. (Cl. 94—11)

Surfacing plates ordinarily are laid in a semi-plastic bedding material, which subsequently hardens, and the plates being laid adjoining each other, form a wear surface for withstanding heavy loads. It is the object of my invention in a floor plate to provide a metallic plate preferably cast from iron, and which has the under surface so formed that the seepage of water to the under surface of the plate will be prevented.

10 Ordinarily plates for heavy duty hauling work are flat both on their upper and lower surfaces, and while, for a time, they are satisfactory, repeated usage and hard wear causes the plates to become displaced. Water or other corrosive 15 liquid seeps in around the edges of the plates and causes deterioration of the material in which the plate is bedded, and for this reason the plates likewise become displaced.

My invention relates to metal floor or surfacing plates which are laid in a plastic bedding material that subsequently hardens, anchoring the plates firmly in position. On the under surface of the metal floor or surfacing plates, projecting continuous fins of dovetail section are placed, 20 which provide the medium for effecting the bond between the plate and the bedding material. The metal floor or surfacing plates are laid with their top surfaces adjoining each other, forming an unbroken surface that will resist wear and prevent the passage of corrosive substances through 25 and between the plates to the bedding material.

It is another object of my invention to provide continuous fins of dovetail section on the under side of the plates and parallel to the perimeter of 30 the plates, in order to seal and protect the bedding material from contact with corrosive substances.

It is still another object of my invention to construct the continuous fin in such a manner that 35 it will act as the means for anchoring the plate to the bedding material, and prevent its displacement or loosening under the action of the forces of the traffic on the plates.

A still further object of my invention is to provide a continuous fin on the under side of the plate, parallel to and near the perimeter, to reinforce the plate at its edges, where the impact of moving loads would subject the plate to the greatest strain.

50 Another object of my invention is to provide a durable metallic surface for the plate in the form of an anti-skid surface which shall be an aid to foot traffic, and will also withstand the impact, hammer and wear caused by heavy moving loads.

It is thus my object to provide a metal floor or surfacing plate which may be made and installed as inexpensively as other forms of surfacing plates, but which will be stronger, more effectively bonded to the bedding material, and will 5 protect the bedding material against the action of corrosive substances appearing on the floor, and will provide a durable floor surface suitable for use under heavy trucking and foot traffic.

The above objects and other objects to which 10 reference will be made in the ensuing disclosure, I accomplish by that certain combination and arrangement of parts of which I have shown several preferred embodiments.

Referring to the drawings:

Figure 1 is a plan view of a preferred type of plate.

Figure 2 is a sectional view taken along the lines 2—2 in Figure 1.

Figure 3 is a bottom plan view of the plate 20 shown in Figures 1 and 2.

Figure 4 is an enlarged sectional view of one of the edges of a modified type of plate.

Figure 5 shows a plate having a slightly different type of bonding fin from that shown in Figures 1 to 3.

Figure 6 is a sectional view of one of the edges of a plate with an air hole in the fin.

The plan view of the plate is shown to be square. The plate could, however, be rectangular 30 or even hexagonal in plan. The hexagonal shape would probably be the ideal shape, but would be more difficult to lay. However, I do not wish to limit myself to any specific outline of the shape of the plate.

The plate which is broadly indicated at 1, has a series of shallow depressions or grooves 2 on its upper surface which form an anti-skid surface which will provide a proper tractive surface for foot traffic. Variations of this anti-skid surface 40 may be desirable, according to users' demands. Spaced slightly from the edges of the plate on its underneath surface, I have shown fins or ribs 3 having the inner sides 5 sloping, which form a secure bond with the semi-plastic material of the bed on which the plates are laid.

In the drawing, Figures 4 and 5, I have shown at 3a, 3b a detailed section of one of the edges of a floor plate having the fins of curved shape.

So that when the plate is laid it will not form air pockets underneath, located in spaced position from the side edges of the plate, I have indicated air vents 6 which permit the escape of confined air when bedding the plate. Figure 6 shows a 55

modification with the air holes 6 in the fin 3 instead of in the plate itself.

To assist in the reinforcing and strengthening of the plate, I have also provided cross ribs 7 extending across the plate from the middle of the edge fins. These ribs 7 are not as deep as the ribs adjacent the side edges of the plate, but they materially increase the bond between the plate and the plastic bed on which the plate is laid. They divide the area of the bottom surface into smaller areas, thus reducing the danger of an air pocket forming under the entire area within the fins.

In laying a floor composed of plates made in accordance with my invention, the plastic, usually cement or asphaltic composition bed, is first laid, and the plates are then arranged end to end and side to side with the fins 3 countersunk in the bed material, but with the level of the plastic bed extending up within the fins against the under surface of the plate. The fact that the inner walls of the fins slope inwardly, as indicated at 5, provides a dovetail interlock with the bed material. If it were not for the air vents 6, which, as indicated, may be conveniently extended through the plate at the bottoms of selected indentations 2, or in the fins themselves, as indicated at 6' in Figure 6, air pockets might be formed which would prevent a perfect bond of the under surface of the plates and the bed material.

One great difficulty with the existing installations of metallic floor plates is that moisture and corrosive liquids seep down around the edges of the plates and corrode the bedding material under the plate. The continuous fins which I provide effectively prevent any seepage which will cause corrosion of the bedding material.

The fins are so positioned relative to the edges of the plates that there is a small space between the fins when the plates are laid adjoining, and the bed material flows up into this space and increases the anchorage of the fins in the bed material.

Floors laid with plates made in accordance with my invention may be subjected to very heavy loads being trucked over them. Due to the perfect bond which is obtainable, these plates will not rock on their bed, and are better adapted to withstand the hammering action of moving loads.

The continuous fins prevent seepage of corrosive liquids underneath the plates. The air vent openings, which prevent the formation of air pockets during laying, will generally be sealed up by the plastic bed material flowing up into them, but may be sealed up mechanically or by solid matter which collects from the traffic on the floor. The fins are arranged on the plates so as to both increase the bond of the plate with the bed, prevent seepage under the plate, and also to materially strengthen the plate's resistance to crushing and loosening strains from moving loads. The cross ribs 7 further aid materially in reinforcing the plate.

It will thus be observed that my invention embodies a floor or surfacing plate made in units which are laid adjoining each other forming an unbroken exposed surface, and embedded in a plastic bed material which later hardens. The continuous fins or ribs near the edges bond the plate to the bedding material and confine and protect the bedding material from possible contact with corrosive substances to which the upper surface of the plates may be exposed. The

plates may be used in constructing a new floor, and may also be used as a resurfacing material for existing floors.

Having thus described my invention, what I claim as new and desire to secure by Letters Pat- 5 ent, is:—

1. A surfacing plate having a continuous bonding rib of uniform depth formed on its under surface, said rib extending parallel with the edges of the plate with a narrow space between the rib and the plate edges whereby, when a plurality of plates are laid on a semi-plastic bed, the bed material will flow into the narrow spaces between the ribs of abutting plates and increase the bonding anchorage of the plate edges in the 15 bed.

2. A surfacing plate having a continuous bonding rib of uniform depth formed on its under surface, said rib extending parallel with the edges of the plate, to form a closed figure with a narrow space between the ribs and the plate edges whereby, when a plurality of plates are laid on a semi-plastic bed, the bed material will flow into the narrow spaces between the rib of abutting plates and increase the bonding anchorage of the plate edges in the bed, and said plate having air vents extending therethrough in that area of the plate outlined by the bonding rib.

3. A surfacing plate having continuous bonding ribs of uniform depth formed on its under surface, said ribs extending parallel with the edges of the plate with a narrow space between the ribs and the plate edges whereby, when a plurality of plates are laid on a semi-plastic 35 bed, the bed material will flow into the narrow spaces between the ribs of abutting plates and increase the bonding anchorage of the plate edges in the bed, said ribs having a depth sufficient to prevent seepage of corrosive liquids to 40 the under surface of the plate.

4. A substantially square metallic surfacing plate having a continuous rib of uniform depth extending down from the under surface of the plate, said rib being arranged parallel to the 45 edges of the plate and spaced therefrom to form a closed figure, and having the inner walls sloping inwardly and having air venting perforations extending through the confining material into the closed figure.

5. A surfacing plate having a continuous bonding rib of uniform depth formed on its under surface, said rib extending parallel with the edges of the plate with a narrow space between the rib and the plate edges to form a closed figure whereby, when the plate is laid on a semi-plastic bed, the bed material will flow completely around the rib and increase the bonding anchorage of the plate edges in the bed, and air vents extending through said rib.

6. A floor or surfacing plate having an upper surface arranged to withstand heavy wear and having a downwardly projecting fin of substantially uniform depth extending from the under-surface thereof parallel to each edge of said plate and spaced inwardly a slight distance therefrom, so that when said plates are embedded in a plastic, said plastic will rise between the juxtaposed fins of adjacent and abutting plates for the purpose described.

7. A floor or surfacing plate having an upper surface arranged to withstand heavy wear and having a downwardly projecting continuous fin of substantially uniform depth forming a closed figure and air vents extending through the con- 75

fining material into said closed figure, the sides of said closed figure paralleling the edges of the plate and slightly spaced therefrom, so that when said plates are embedded in a plastic, said plastic will rise between the juxtaposed fins of adjacent and abutting plates for the purpose described.

8. A substantially square metallic surfacing plate having continuous ribs of uniform depth 5 extending downwardly from the under surface thereof, said ribs being parallel with the four edges of the plate and slightly spaced therefrom, and having their inner sides sloping inwardly.

9. A surfacing plate having a continuous bonding rib of uniform depth formed on its under surface, said rib extending parallel with the edges of the plate to form a closed figure with a narrow space between the rib and the plate 5 edges, whereby, when a plurality of plates are laid in a semi-plastic bed, the bed material will flow into the spaces between the ribs of abutting plates and prevent a seepage pocket forming between the plates, and said plate having air 10 vents extending therethrough in that area of the plate outlined by the bonding rib.

VERNON G. HECHT.
